UNITED STATES PATENT OFFICE.

GEORGE HIVES DAWSON AND HURXTHAL FIELD FREASE, OF BOSTON, MASSACHUSETTS.

TRUSSED STRUCTURE.

Application filed July 17, 1924. Serial No. 726,489.

To all whom it may concern:

Be it known that we, GEORGE HIVES DAWSON and HURXTHAL FIELD FREASE, citizens of the United States, residing at Boston, in the county of Suffolk and State of Massachusetts, have invented new and useful Improvements in Trussed Structures, of which the following is a specification.

The invention relates to trussed structures of the type set forth in our joint application for United States Letters Patent, Serial No. 676,897, filed November 26, 1923, comprising spaced chord members and connecting web members joined together and formed from continuous strip, bar, or rod material.

The present invention relates more particularly to continuous strip trussed structures having chord members of different cross-section than the web members; the difference in cross-section being achieved by varying the geometric outlines of the continuous strip, bar, or rod material from which the structures are made.

The objects of the present invention are to provide trussed structures made from continuous strip, bar, or rod material having varying geometric outlines; the types of such structures including among others, trussed I structures and T structures; internally trussed tubing; and trussed structures having channel or tubular chord members.

Several practical means of attaining these objects are illustrated by the accompanying drawings, in which—

Figure 1 is an isometric view of a length of continuous strip trussed I structure;

Fig. 2, an isometric view of a length of the blank for the same;

Fig. 3, an isometric view of a length of the blank partially formed to make the trussed I structure;

Fig. 4, an oblique perspective view of a length of continuous strip trussed structure having channel chord members;

Fig. 5, an oblique perspective view of a length of the blank for the same with the channel chord members already formed;

Fig. 6, an oblique perspective view of a length of the blank for a continuous strip

trussed I structure having chord members comprising plural, overlapped strips;

Fig. 7, an oblique perspective view of the same partially formed to make the I structure;

Fig. 8, an oblique perspective view of a length of the continuous strip trussed I structure having chord members comprising plural, overlapped strips;

Fig. 9, an oblique perspective view of a length of the continuous strip trussed structure in the form of an internally trussed rectangular tube, a portion of the tube showing in cross-section at intersecting planes IX-IX and X-X;

Fig. 10, an oblique perspective view of a length of the blank for the same; and

Fig. 11, a length of continuous strip trussed structure having rectangular tube chord members, showing some of the chord members before forming.

For the purposes of clearness of illustration no fastening means are shown. In the structures illustrated the fastening means are presumed to be some form of welding, spot, seam, butt, arc, or acetylene, which will be designated in connection with the detailed description of each type.

It is obvious, however, that rivets, or any other desired mechanical fastening means may be used in place of the presumed welds for joining together the members of the trussed structures.

Moreover, the material used may be unperforated as shown, or may be perforated, or may be made of expanded metal of any desired type.

Similar characters of reference indicate similar parts throughout the drawings.

The various improved trussed structures S¹, S², S³, S⁴, and S⁵ shown, respectively, in Figs. 1, 4, 8, 9, and 11, comprise, respectively, spaced chord members of various cross-sections C¹, C², C³, C⁴, and C⁵, and connecting web members W¹, W², W³, W⁴, and W⁵, respectively, alternating with, continuous with, and connected to the chord members. The connecting or fastening means, not shown, used at the junctions of the chord and web members are presumed to

be the forms of weld presently to be described, although other fastening means may be used. It must be clearly understood, however, that some form of fastening means must be used to join the chord members and web members at the junctions of the various structures.

The I structure S^1 is made from the strip blank S^{1b} , which is shown partially formed 10 as S^{1t} , and comprises chord members C^1 of one cross-section, alternating and continuous with web members W^1 of another cross-section; the alternating and continuous chord and web members being bent at their 15 lines of intersection I—I, as shown partially bent in S^{1t} , to form opposing junction angles A^1 . Where required, slits k^1 , extending the web members into the chord members, permit the bending of the junction 20 angles.

To make the structure S^1 the blank S^{1b} as shown has been cut from a strip of material having a uniform thickness or depth d^1 , but the strip material may have a varying thickness; so that the chord members C^1 may 25 have a different thickness than the web members W^1 .

In the blank S^{1b} as shown the chord members and the web members have rectangular 30 outlines, but the outlines might be trapezoidal.

As shown, however, the chord members C^1 and the web members W^1 have the same depth d^1 ; but the chord members have a breadth b^1 greater than the breadth b^{1t} of the web members. The length I^1 of the chord members C^1 and the length I^{1t} of the web members W^1 may have any desired ratio to each other. Likewise the ratio of b^1 40 to b^{1t} may be different than that illustrated where b^1 is greater than b^{1t} .

However, as may readily be seen from the drawings, the differences in the structures S^1 , S^2 , S^3 , S^4 , and S^5 , are primarily determined by the respective differences between 45 the similar dimensions d^1 , d^2 , d^3 , d^4 and d^5 ; b^1 , b^2 , b^3 , b^4 , and b^5 ; b^{1t} , b^{2t} , b^{3t} , b^{4t} , and b^{5t} ; I^1 , I^2 , I^3 , I^4 , and I^5 ; I^{1t} , I^{2t} , I^{3t} , I^{4t} , and I^{5t} ; and k^1 , k^2 , k^3 , k^4 , and k^5 ; of the chord 50 members, C^1 , C^2 , C^3 , C^4 , and C^5 , and the web members W^1 , W^2 , W^3 , W^4 , and W^5 ; of the structures.

In the structure S^2 , the length of the slits k^2 permits the overlapping of the opposing and abutting chord members C^2 . Equal legs h^2 have been bent as shown from the material in the blank S^{2b} to form the channel chord members C^2 .

The structure S^3 , differs primarily from S^2 in the relative proportions of the dimensions of the chord and web members. The length of the slits k^3 is sufficient to permit the opposing chord members to overlap each other to form the structure illustrated. The

material in the chord members might have 65 been bent to form channel chord members.

Likewise the internally trussed tubular structure S^4 , differs primarily from the I structure S^1 in the relative dimensions of the chord and web members. The lengths 70 of the legs h^4 permit the forming of the closed tube upon bending the material in the chord members as shown.

Finally the structure S^5 is provided with its tube chord members C^5 as shown by 75 forming the material of the blank chord members.

The structure S^1 is adapted to butt or arc welding as a fastening means at the junction angles A^1 . The structures S^2 and S^3 80 are obviously adapted to spot welding as a fastening means for the overlapped chord members. The structures S^4 and S^5 are adapted to arc and seam welding at the junctions and the seams.

The feature of overlapping chord members shown in structures S^2 and S^3 might be applied to structures S^4 and S^5 .

The essence of the invention lies in the provision for any desired variations in form 90 or area between the chord and web members of continuous material trussed structures by suitably fixing the geometric outline of the blank stock and performing any desired forming operations to the chord or web 95 members.

We claim:

1. A trussed structure formed from a single continuous strip, including chord members and web members, there being 100 junction angles between the chord and web members and means fastening the chord and web members to each other at the junction angles, some of the chord members having a different cross-sectional area than 105 the web members.

2. A trussed structure formed from a single continuous strip, including chord members and web members, there being 110 junction angles between the chord and web members and means fastening the chord and web members to each other at the junction angles, some of the chord members being of different formed cross-sectional area than the web members.

3. A trussed structure formed from a single continuous strip including chord members and web members, there being junction angles between the chord and web members and means fastening the chord and 120 web members to each other at the junction angles, some of the chord members having a different cross-sectional area than the web members, and overlapping each other at the junction angles.

4. A trussed structure formed from a single continuous strip, including chord members and web members, there being 125

junction angles between the cord and web members and means fastening the chord and web members to each other at the junction angles, some of the chord members being formed channels.

5. A trussed structure formed from a single continuous strip, including chord members and web members, there being

junction angles between the chord and web members and means fastening the chord and web members to each other at the junction angles, some of the chord members being formed angles.

GEORGE HIVES DAWSON.
HURXTHAL FIELD FREASE.
